John E. Prager

UNITED STATES PATENT OFFICE

CHARLES GRIMM, OF BROOKLYN, NEW YORK

INCANDESCENT LAMP SOCKET

Application filed January 15, 1931. Serial No. 508,902.

This invention relates to electrical connections of the separable snap type as applied to plug and socket devices, of which a common incandescent lamp is taken as an illustration.

Customarily such lamps are provided with plugs having shallow, coarse pitch screw threads to engage in corresponding threads in the socket member and must be entered to the limit in order to cause the tip at the end of the plug to form electrical engagement with the contact carried within the bottom of the socket.

If subjected to jars, vibrations, etc., it is found that such coarse, smooth screw threads readily become loosened to the extent of breaking the contact, putting the lamp out of operation; it also requires some degree of mechanical skill to properly attach and adjust the lamp to its socket.

It is therefore an object of the present invention to provide a novel and efficient type of electrical connection in which a direct thrust of the plug into the socket only is required.

A further feature is in the provision of means whereby the plug is positively held within the socket in a manner proof against accidental displacement and in direct engagement with the electrical contacts carried by it, safely, surely and efficiently, until it is desired to remove the lamp, accomplished by a direct, straight pull.

Another aim is to produce a form of connection, neat and attractive in appearance, and which can be manufactured at a moderate cost as compared with present types of connections.

Still another object is to provide means whereby common screw sockets may be inexpensively changed to conform with the present disclosure.

These several advantageous objects are attained by the simple and novel construction, combination and arrangement of parts hereinafter described and illustrated in the accompanying drawings, forming a material part of this disclosure, and in which:—

50 Figure 1 is a side elevational view of an

embodiment of the invention, parts being broken away to show the construction.

Figure 2 is a longitudinal sectional view of the socket, the lamp and its plug being in side elevation.

55 Figure 3 is a bottom plan view of the socket.

Figure 4 is a developed plan view of the socket carried clamp device.

An ordinary type of incandescent lamp 60 bulb is generally designated by the numeral 10, the same being shown as spherical with a neck 11 contracted and extended to be rigidly set in its non-conducting plug and provided with the usual filament, one terminal of which 65 is fixed in electrical engagement with a metallic tip 14 set in the end of the plug.

A metallic sleeve 15 is fixed on the body of the plug circumferentially, the same being in electrical engagement with the other terminal of the filament.

70 Formed in the sleeve 15 are a plurality of uniform semispherical indentations 16 arranged in equal spaced relation in two or more circumferential rows.

75 The socket includes the usual casing 20, reduced in diameter at its lower portion 21, beaded at 22 near its lower end, and provided with a cap 23, the flange 24 of which overlies and is secured to the upper portion of 80 the casing.

A conductor 25 enters the cap through a central insulated bushing 26, one of the conductor strands engaging a contact 27, preferably of spring metal anchored as at 28, 85 see Figure 3.

80 A lining 30 of non-conducting material is disposed in the form of a hollow cylinder within the socket element 21, all of the several parts being common and of well known 90 construction.

A conductor plate 31, shown in blank form in Figure 4, is sheared to present a series of spring clips 32—33 directed alternately in opposite directions and centrally 95 in each clip is a detent 34—35 shaped to conform to the indentations 16.

The upper portion of the plate 31 is 100 bent at a right angle to form an annular flange 36 secured by screws 37 within the

socket, as best seen in Figure 2, and it is to be understood that the length of the plate is such as to form a band fitting within the non-conducting lining 30.

5 The spacing of the detents 34-35 is in accordance with the distance apart of the rows of indentations 16 of the plug sleeve 15, in the direction of the axis of the lamp, and are laterally spaced to agree with the 10 distance apart to multiples of the indentations 16, so that upon pressing the lamp plug into the socket, the detents will snap into corresponding indentations.

15 In changing a common threaded socket to the type herein described, it is necessary only to remove the internal screw-threaded sleeve and secure the flanged band in its place, no other change being required.

20 Thus a socket so equipped may be used with a plug made in the manner described, and which will be held so firmly that no shock, jar or vibration can affect the electrical connections.

25 Obviously a straight push only is required to enter and engage the plug, and it is equally evident that disengagement is equally easily effected by a corresponding straight pull.

30 Although the foregoing is descriptive of the best known embodiment of the invention, it will be understood that changes and modifications may be resorted to as may be embraced within the scope of the appended claims.

35 Having thus described the invention, what is claimed as new and desired to secure by Letters Patent, is:—

1. A separable electric connection comprising a socket, a plug engageable therein by direct thrust and removable therefrom by direct pull, a single flat spring contact in said socket to engage a contact on the tip of said plug, a plurally indented contact sleeve on said plug, a band contact fixed 40 in said socket to receive said sleeve, and a series of spring detents on said band contact to engage the indentations of said sleeve.

45 2. A separable electric connection comprising a socket, a plug engageable therein by direct thrust and removable therefrom by direct pull, a spring contact in said socket to engage a contact on the tip of said plug, a conducting sleeve on said plug, said sleeve having circumferential rows of indentations, a band contact fixed in said socket circumjacent said sleeve, a series of spring clips sheared from said band, and detents carried on said clips in planes corresponding to 50 the rows of indentations to engage therein.

55 3. A separable electric connection comprising a socket, a plug engageable therein by direct thrust and removable therefrom by direct pull, a single flat spring contact in said socket to engage a contact on the

tip of said plug, a conducting sleeve on said plug, said sleeve having two or more circumferential rows of indentations, a band contact fixed in said socket circumjacent said sleeve, a series of spring clips sheared from 70 said band in opposed inreaching relation, and detents formed in said clips to extend inwardly in two different planes for engagement in different rows of indentations in said sleeve and at spaced intervals therein. 75

In testimony whereof I affix my signature.
CHARLES GRIMM.
